UNITED STATES PATENT OFFICE.

GEORGE RILEY IVES, OF WEST PIKE, ULYSSES, PENNSYLVANIA.

BRICK-CLEANING MACHINE.

1,312,989.

Specification of Letters Patent. Patented Aug. 12, 1919.

Application filed May 1, 1917. Serial No. 165,754.

To all whom it may concern:

Be it known that I, GEORGE RILEY IVES, a farmer, citizen of the United States, residing at West Pike, Ulysses, R. F. D. 2, in the 5 county of Potter and State of Pennsylvania, have invented certain useful Improvements in Brick-Cleaning Machines, of which the following is a specification, reference being had therein to the accompanying drawing.

10 The invention relates to a brick cleaning machine, and has for its primary object to provide a machine of this character wherein used bricks can be cleaned by the removal from the surfaces thereof of mortar, cement, 15 or the like, with despatch, thereby eliminating the hand cleaning of the same and thus minimizing labor for this purpose.

Another object of the invention is the provision of a machine of this character 20 wherein the cutting wheel is adapted to be driven from a motor so that a single operator is required in the handling of a machine, and a maximum number of bricks can be cleaned with minimum labor and time.

25 Still another object is the provision of a brick cleaning machine, the grinding disk of which is completely shielded, the shield having an opening formed therein to permit bricks to be presented to the grinding 30 surface of the disk. The edges of this opening formed in this shield are beveled, both for the purpose of grinding mortar off the corners of bricks and for the purpose of 35 permitting the easy removal of bricks after having been subjected to the grinding operation.

A further object of the invention is the provision of a machine of this character, which possesses simplicity in construction, 40 durability, efficiency in operation and also one which may be manufactured at a minimum cost.

Other objects will be in part obvious and in part hereinafter set forth.

45 The invention accordingly consists in the features of construction, combination of elements and arrangement of parts which will be exemplified in the construction hereinafter described, and the scope of the application of which will be indicated in the appended claims.

In the accompanying drawings:

Figure 1 is a side elevation of the machine constructed in accordance with the invention; 55 Fig. 2 is a top plan view;

Fig. 3 is a perspective view of the cutter wheel;

Fig. 4 is a view similar to Fig. 1, but looking toward the opposite side of the machine.

60

Fig. 5 is an elevation;

Fig. 6 is a vertical transverse sectional view on the line 6—6 of Fig. 1.

Similar reference characters indicate corresponding parts throughout the several 65 views of the drawing.

Referring to the drawing in detail, the machine comprises a frame A having a top section 10 and legs 11, with upper and lower braces 12 and 13 respectively, the braces 12 70 being connected to the top section 10 and said legs 11, while the braces 13 connect the legs 11 together at their lower ends, thereby assuring a rigid frame structure.

Upon the side walls of the top section 10, 75 medially thereof, are block bearings 14 in which is journaled a driven shaft 15 which extends transversely of the frame and has fixed to its rear end a belt pulley 16 over which is adapted to be trained a suitable 80 belt driven from a motor which may be of any desirable type.

Next to the front side of the frame A and keyed upon the driven shaft within the top section of said frame is a cutter which is in 85 the form of a disk 17 provided at its outer side with radially disposed cutting teeth 18 which are disposed concentrically of the shaft 15 and are adapted to cut and remove mortar, cement or the like from faces or corners of a brick when presented to the machine in a manner hereinafter described.

The front side of the frame A has mounted thereon a covering 19, and fixed to this covering is a work support 20 for the positioning of a brick thereon to present the same to the cutting teeth 18 of the cutter, the covering 19 being formed with an opening or slot 21 through which is passed the brick to bring the same into the path of the 100 cutting edges of the teeth 18 of said cutter, and when the latter is rotated the teeth will remove all mortar, cement or the like from the face of the brick and in this manner the said brick will be cleaned of the material 105 or matter adhering thereto so that said brick can be reused for building purposes.

The opening or slot 21, it will be observed, is provided with beveled edges both at its top and at either end. This arrangement 110

provides for the easy removal of the brick from the grinding face of the disk 17 when the mortar has been completely removed therefrom, the sliding of the brick along in 5 the direction of the length of the support 20 bringing the end of the brick into contact with the beveled edge at that end of the opening in the direction of which the brick is moved. This beveled edge then serves to 10 gradually direct the brick away from the grinding disk as the longitudinal movement of the brick is continued. This arrangement obviates the necessity for having to pull the brick sidewise away from the 15 grinding disk, such as would be necessary were the beveled edges not provided. This arrangement of the beveled edges greatly facilitates the grinding operation in that it permits it to be done more quickly, an operator simply sliding the brick along the support 20 until it drops in against the face of the grinding disk. When the mortar has been removed, the sliding movement being again given to the brick, it is continued to 25 the other end of the work support, the beveled edge of the opening, as before stated, directing the brick away from the grinding disk. Thus it is not necessary for an operator after grinding brick to move to a position 30 where he has to pull the brick laterally away from the disk.

The beveled edge at the top of the opening 21 performs the same function as do the other beveled edges by directing the brick away from the grinding disk, if the mortar is being removed by raising and lowering the brick as it is being operated upon by the grinding disk. Again, the side beveled edges of the opening provide for effectively 35 removing mortar from the corners of bricks, these beveled edges providing a substantial support for holding a brick in such an angular position on the support 20 that its edge is presented to the teeth of the grinding disk.

The upper end of the covering 19 is upwardly bowed or convexed and has fixed

thereto an upwardly bowed guard or shield 22 which overlies the cutter so as to prevent the loosened material or dust, dirt or 50 the like from flying, to the detriment of the operator of the machine.

From the foregoing description, taken in connection with the accompanying drawing, the construction and operation of the herein described brick cleaning machine will be readily apparent and, therefore, a more extended explanation has been omitted.

Having thus described my invention, I claim:

1. A machine of the character described comprising a supporting frame, a shaft journaled transversely thereon, a disk mounted on the shaft and having teeth on its outer side thereby forming a cutter, a covering on 65 the supporting frame completely shielding the disk on the toothed side of the latter, the covering having a rectangular opening to expose the teeth of the disk, and a supporting shelf attached to the covering and adjoining the lower edge of the opening and extending beyond either end thereof, the said opening having its top and end edges beveled in toward the disk whereby bricks may be slid along the shelf for presentation 75 to the disk, the beveled edges of the opening serving to direct the bricks away from the disk as the sliding is continued.

2. A machine of the character described comprising a supporting frame, a rotary 80 disk mounted in the frame and having cutting teeth on its outer side, and a covering mounted on the frame and shielding the disk on the tooth side of the latter, the covering having an opening formed therein to expose the cutting teeth, the opening having its edges beveled in toward the disk, whereby a brick being operated upon may be easily directed away from the disk or supported in an angular position with respect 85 to the disk for grinding upon the edges of the brick.

In testimony whereof I affix my signature.
GEORGE RILEY IVES.
